CLAIM

The ornamental design of a combined candle and candleholder therefor, as shown and described.

DESCRIPTION

FIG. 1 is a perspective view of the combined candle and candleholder therefor showing my new design;

FIG. 2 is a top plan view therefor;

FIG. 3 is a bottom plan view therefor;

FIG. 4 is a side elevation view therefor;

FIG. 5 is a side elevation view therefor and which is taken from a position opposite to that which is shown in FIG. 4;

FIG. 6 is a side elevation view therefor and which is taken from a position approximately at a right angle relative to that which is shown in FIG. 5; and,

FIG. 7 is a side elevation view therefor and which is taken from a position opposite to that shown in FIG. 6.

FIG. 5

FIG. 7

FIG. 4

FIG. 6

FIG. 1

FIG. 3

FIG. 2
